PRESSURE ADJUSTING DEVICE

Paul Dietrich, Augsburg, Germany, assignor to
 Maschinenfabrik Augsburg-Nürnberg A. G.,
 Augsburg, Germany, a corporation of Germany

Application April 17, 1937, Serial No. 137,433
 In Germany October 26, 1935

2 Claims. (Cl. 101—247)

In rotary photogravure machines the web to be printed passes between two cylinders which are pressed against each other and of which one, the impression cylinder, to adjust the degree of pressure is moved towards the other cylinder, the form cylinder, or away therefrom. It has hitherto been impossible to adjust the degree of pressure accurately enough or, after, a temporary alteration thereof to restore the earlier condition

- 10 because the mechanical means applied to this end lacked precision and were too complicated and unreliable in their action. Accurate adjustment is however indispensable, for instance in multi-color printing, because proper register of the several succeeding impressions can be obtained only if the tension of the web be kept even, and the tension varies with the degree of pressure between the cylinders. If in machines equipped with any of the known adjusting devices the web 20 during the run accidentally breaks, the machine is liable to get unduly strained and damaged through the rear end of the broken web getting wound around one of the cylinders or an intermediary roll disposed between the two cylinders. 25 The object of the invention is a pressure adjusting device of high precision which has none of these drawbacks.

According to the invention the impression cylinder consists of a rotatable jacket on an eccentrically journalled core, which core if rocked one way or the other will either bring the impression cylinder nearer to, or remove it further away from the form cylinder, thereby adjusting the degree of pressure. The rocking motion is effected by 30 means of two pneumatic cylinders, one each for effecting either movement.

Fig. 1 of the drawing is a side view of a preferred form of the device according to the invention;

40 Fig. 2 a longitudinal section thereof.

The printing mechanism comprises a form cylinder 1, an intermediary roll 2 and an impression cylinder, the jacket 3 of which rotates on the core 4 of the cylinder. The eccentrically 45 to the jacket 3 located journal 5 of the core 4 and the intermediary roll 2 are carried by a slidale frame 6 which by means of a screw spindle 7 and a worm-gear 9, 10 in the main frame of the printing machine may be moved vertically within 50 wide limits for rough adjustment, or when exchanging a form cylinder of a certain diameter

against one of different diameter. Rigidly connected with the journal 5 is a two-arm lever 11 which by means of the two piston rods 12 and 13 of the pneumatic cylinders 14 and 15 may be turned one way or the other. The action of the pneumatic cylinders is controlled by two three-way cocks 16 and 17 which at will establish communication either with the delivery pipe or the outer air. Pressure is regulated by means of a reduction valve 18.

10 In place of the two single-acting pistons 14 and 15 one double-acting piston may be used.

The two three-way cocks 16 and 17 may also be replaced by one double-acting one.

As represented in the drawing the impression 15 cylinder 3 will be brought closer to the form cylinder if the piston 14 moves to the right, and removed therefrom if the piston 15 is moved to the right. Since the intermediary roll 2 is pressed 20 against the impression cylinder by a spring 20, also disposed within the slidale frame 6, it will follow its every movement.

Instead of the pneumatic cylinders, other means such as hydraulic, mechanical or electrical means 25 may be used to act on the lever 11 in the manner described. The pneumatically actuated adjustment device has however the advantage of being elastic, thereby preventing undue strain on any of the separate parts of the printing mechanism in 30 case of breakage of the web and consequent troubles.

Having now particularly described and ascertained the nature of my said invention and in what manner the same is to be performed, I declare what I claim is:

1. In a rotary printing press, in combination with the form cylinder, a cylindrical core rotatably supporting an impression cylinder and having journals eccentric relative to said impression cylinder, bearings for said journals, a two-arm lever attached to one of said journals, and means connected to the arms of said lever for pivoting the same in either direction for turning said core to thereby adjust the position of said impression cylinder relative to said form cylinder.

2. The combination as specified in claim 1, in which said means for pivoting said lever comprises two pneumatic cylinders, movable pistons in said cylinders, and piston rods connecting said pistons with the arms of said two-arm lever.

PAUL DIETRICH.
